UNITED STATES PATENT OFFICE.

JOHN HANSEN, OF PORT CHESTER, NEW YORK, ASSIGNOR TO ABENDROTH BROTHERS,
OF PORT CHESTER, NEW YORK, A CORPORATION OF NEW YORK.

GAS RANGE.

Application filed December 6, 1923. Serial No. 678,925.

To all whom it may concern:

Be it known that I, JOHN HANSEN, a citizen of the United States, residing at Port Chester, in the county of Westchester and State of New York, have invented new and useful Improvements in Gas Ranges, of which the following is a specification.

The present invention relates to improvements in gas ranges, and particularly to ranges of the type in which the compartment or space in which the burners are arranged is provided with a substantially solid metal cover or top.

The particular object of the present invention is to provide such a solid top gas range with means whereby the openings or apertures provided in the top for the reception of cooking vessels or receptacles may be closed in such manner as to provide a continuous smooth surface throughout the top area.

A further object is to provide the top of such a range with means for supporting within each vessel or receptacle aperture therein a grate or grid, which with its supporting means will be completely concealed when the apertures referred to are closed by removable cover plates.

With the foregoing and other ends in view, the invention resides in the construction and arrangement of parts that will be hereinafter more particularly described and claimed.

In the accompanying drawing there is illustrated one embodiment of the invention, but it will be understood that some of the parts are shown more or less conventionally, and, of course, there can be variation in the proportions and form of the several parts without departing from the invention.

In the drawings:

Figure 1 is an elevation of a portion of a gas range constructed in accordance with the invention, part of the top being broken away.

Figure 2 is a plan, on an enlarged scale, of a portion of the closed top and one of the utensil supporting grids or grates.

Figure 3 is a transverse section substantially on the line 3—3 of Figure 2 illustrating a slight modification.

Referring to the drawings, in the several views of which corresponding parts are designated by like characters, 1 indicates a gas

range, which may be of any suitable size and form. The particular form of range illustrated is provided with an elevated oven and has a solid top 2 above the chamber or compartment in which the burners 3 are arranged.

The top 2 is formed of a metal casting having depending marginal flanges at the sides and front, the latter being shown as extending downward to the plane of the main gas supply pipe 4 and provided in its lower edge with recesses which receive the mixing valves 5, through which the branch burner supply pipes extend. As is usual, the supply of gas to each burner is controlled by a suitable cut-off 6.

The top 2 is provided above each burner with an aperture or opening adapted to receive a cooking utensil and within each such opening is arranged a grid or grate 7 on which the utensil may rest.

As shown, the grid or grate 7 is supported at its margin by means integral with the top 2, and said grid is of such thickness that its upper surface is on a level considerably below the plane of the upper surface of the top 2.

Each of the utensil receiving apertures in the top 2 is adapted to be closed by an imperforate cover plate 8 of such thickness that it will, when resting on the grid 7, have its upper surface in the plane of the top so that the latter will present a smooth unbroken surface when the several cover plates 8 are in position.

It will be seen that the grids or grates 7 and the cover plates 8 are of the same dimensions and form as the utensil receiving openings in the stove top, and, therefore, the construction provides for a minimum amount of joint or separation space between the several opening closures and the main body of the top 2.

The support for the grate 7 may, as shown in Figures 1 and 2, be a horizontal flange 9 extending continuously around the utensil opening in the top plate and projecting inwardly therefrom or may consist merely of suitably spaced lugs 10 formed integral with the plate 2, as shown in Figure 3.

The removable cover plates or lids 8 are shown as being of slightly greater thickness at the marginal portions thereof than throughout their body, thereby providing a depending marginal rib which rests di-

rectly on the marginal ring of the grid or grate 7.

As before pointed out, when the lid or cover plate 8 is in position, it completely covers the grid or grate 7 by which it is supported, and as said plate or lid conforms closely in dimensions and shape to the form of the utensil receiving opening in the top 2, it will be seen that said openings are completely closed and a uniformly smooth surface provided throughout the top.

It is believed that the advantages of the improvements will be readily understood and appreciated from the foregoing description in connection with the drawing.

I claim:

1. In a gas stove, the combination with a burner, of a top plate provided with an aperture above the burner adapted to receive a cooking utensil, a removable grid supported within said aperture entirely below the plane of the upper surface of the top plate, and a removable cover plate of sub-

stantially the same diameter as the aperture supported on the grid and having its upper face flush with the surrounding surface of the top plate. 25

2. In a gas stove, the combination with a burner, of a top plate having an aperture above the burner adapted to receive a cooking utensil, and provided on its lower face about said aperture with a plurality of depending lugs, a removable grid positioned within said aperture and supported by said lugs, and a removable cover plate of substantially the same diameter as the aperture supported on the grid, and having its upper face flush with the surrounding surface of the top plate. 30 35

In testimony whereof I have hereunto set my hand.

JOHN HANSEN.
